UNITED STATES PATENT OFFICE.

EDWARD I. RICE, OF SYRACUSE, NEW YORK.

SELF-CANCELING COUPON.

1,330,217.

Specification of Letters Patent. Patented Feb. 10, 1920.

Application filed January 9, 1919. Serial No. 270,316.

To all whom it may concern:

Be it known that I, EDWARD I. RICE, citizen of the United States of America, and resident of Syracuse, in the county of Onondaga, in the State of New York, have invented new and useful Improvements in Self-Canceling Coupons, of which the following, taken in connection with the accompanying drawings, is a full, clear, and exact description.

This invention relates to a new and useful self-canceling coupon produced in integral strips consisting of a plurality of such coupons. This application is a continuation in part of my copending application, Serial Number 261,477.

The coupon method of selling merchandise involves the purchase of coupons by the prospective buyer and the payment for merchandise by such coupons properly marked as exchangeable for a predetermined quantity of merchandise so that the sale of the merchandise does not in itself involve a transfer of money.

Coupons become lost or are given away or sold by drivers and others delivering merchandise, and a considerable quantity of them are reused in exchange for merchandise without the seller of the merchandise receiving any consideration for the same. This results from the fact that the coupon is, at all times, negotiable by the bearer to the extent of its exchange and value in merchandise.

In certain characters of business done on coupon basis one of which is here specifically referred to as illustrative viz: the sale of ice, the seller loses large quantities of ice by reason of the negotiability of these coupons. The primary object of this invention is, therefore, to produce a self-canceling coupon that when once used is no longer negotiable, and preferably contains upon its face a statement as to its prior use or non-negotiability.

Another object relates to the production of a sales record in connection with each coupon strip by means of which a record of the sale of each coupon strip is obtained and which constitutes a check disclosing unauthorized use of the coupons. A further object relates to the mutilation of the coupon when exchanged for merchandise so that it no longer has a representative value rendering it negotiable.

As illustrative of a preferred form of my

invention I have disclosed a coupon strip consisting, in this instance, of a sales record and three coupons vertically arranged beneath the sales record, the sales record and each of the coupons united by a common header constituting a fourth coupon, the sales record and the coupons being separated from each other and from the header by any suitable indicating means as lines which, in this preferred embodiment, take the form of a series of alined perforations permitting easy separation of the sales record, the coupons and the header.

In the drawings:

Figure 1, is a face view of a coupon strip of my invention.

Fig. 2, is a rear view of the same.

Fig. 3, is a rear view similar to Fig. 2, and including a modification of the word arrangement upon the coupons and header.

As illustrated in the drawings, my invention takes form in a strip, —1— of suitable material, as paper, cardboard, or the like, divided vertically by line 2 into two sections, three and four, respectively, the section —3— divided by horizontal lines —5— into a sales record —6— and a series of similar coupons —7—. In this illustration I have shown three such coupons, but in actual practice my coupon strip consists of eight coupons, seven of which are vertically arranged, one above the other. The lines, —2— and —5— are preferably formed by alined perforations, or the material may be otherwise weakened along these lines to permit easy separation of the parts. The section —4— constitutes a header integrally united to the sales record and each of the vertically arranged coupons, and in itself constitutes an additional or last coupon, preferably of equal value with each of the other coupons.

The portion of the coupon strip referred to as the sales record portion is preferably formed at the upper end of the section —3—, and bears a number, in this instance, "Number 1006," and each coupon bears the same number thereby identifying the coupon as forming or having formed a portion of a coupon strip of that number. The sales record also bears indicia indicating its designed use as, for instance, the words "Sales record" together with blank spaces for receiving the name and the address of a person purchasing the coupon strip and also the amount of merchandise for which the entire

strip is exchangeable and the amount of money for which the coupon strip is sold as, for instance, "200 lbs. ice \$1.00." It may also contain blank spaces for receiving the route and number of the salesman selling the coupon. When the coupon is sold the sales record is detached and retained by the salesman and filed for future reference. Each coupon bears a number preferably beginning with number 1, and continuing consecutively downwardly through the vertically arranged coupons and terminating with the last consecutive number upon the header or last coupon. The front of the coupon strip bears the name of the seller of the coupon or the person who will exchange a predetermined quantity of merchandise for the coupon and this name appears upon each vertically arranged coupon and the adjacent portion of the header or last coupon, for instance, "John Doe Co." a portion of this name appearing upon each coupon and the other portion upon the adjacent part of the header so that when the coupon is detached from the header only a part of the name appears thereon.

Under this name, and upon each coupon and the adjacent portion of the header appears a statement in substance as follows: "Sold only in strips of two or more coupons. No ice sold for cash," and as a portion of this statement is on each coupon and the other portion upon the adjacent part of the header it is apparent when the coupon is detached from the header that it has constituted a part of a coupon strip and by its removal from the remaining portions of the strip has been mutilated and rendered incomplete. Each coupon, including the header, contains indicia showing the quantity of merchandise for which it is exchangeable. The header contains a statement to the effect that "This strip represents the last coupon and should be turned in for 50 lbs. of ice. Not good if mutilated," preferably written vertically of the header.

As shown in Fig. 2, the rear of the sales record preferably contains the name of the person or company appearing across the face of the coupon strip, and may contain other information such as the address, phone number, etc., together with a space for receiving remarks that the salesmen or others may care to make with regard to related matter. The rear of each of the vertically arranged coupons contains a statement to the following effect "This coupon has been used and is therefore not negotiable for ice." The rear of the header strip or last coupon contains a statement to the following effect: "This strip represents the last coupon and should be turned in for 50 lbs. of ice. Not good if mutilated," also "Notice—use coupons first, then for the last use this coupon strip," and preferably opposite the

adjacent end of each coupon there is a statement as follows: "Not good if mutilated."

In Fig. 3 I have disclosed the rear of a coupon strip similar in all respects to the coupon strip of Fig. 2 except that the words "Not good if mutilated" are so arranged upon the header or last coupon as to read in conjunction with the statement upon the coupons, across the coupon and the header to indicate that while the coupon is attached to the header it has not been used, and is, therefore, good, but is not negotiable when mutilated by detachment from the header. The statement upon the coupon itself remains the same.

The result of this construction of coupon strip is that the seller has, at all times, a complete record of sales, both of coupon strips and of merchandise exchanged for all or any portion thereof, and ultimately when the entire exchange has been completed receives all portions of the coupon strip as it was originally produced for sale. The vertically arranged coupons are only exchangeable for merchandise while they remain attached to the header, or last coupon and are mutilated by detachment therefrom preventing their sale by drivers of delivery wagons or other persons collecting coupons in exchange for merchandise. When the header strip or last coupon is turned in all of the coupons of the same number should likewise be in the possession of the seller of the merchandise and if they are not they are at least not negotiable either for sale or for exchange.

Although I have shown and described a specific physical structure with particular indicia and wording thereon, as illustrative of a perhaps preferred form of my invention, I do not desire to limit myself to the same in the exact form illustrated as various equivalent forms, indicia and words may be substituted for those shown without departing from the spirit of this invention as set forth in the appended claims.

What I claim is:

1. A coupon strip divided vertically into two sections, one of said sections divided horizontally into a series of coupons, arranged vertically one above the other, and the other section bearing indicia constituting it an additional coupon and forming a header uniting all the coupons, the name of the seller appearing upon each coupon and the adjacent portion of the header shows that such name is mutilated by detachment of the coupon from the header.

2. A coupon strip divided into two sections, one of said sections divided into a sales record and a series of coupons, the other section constituting a header uniting the sales record and the coupons.

3. A coupon strip divided into two sections, one of said sections divided into a

sales record and a series of coupons, the other section constituting a header uniting the sales record and the coupons, said header indicated to constitute an additional coupon.

4. A coupon strip divided vertically into two sections, one of said sections divided horizontally into a series of coupons arranged vertically one above the other and the other section bearing indicia constituting it an additional coupon and forming a header uniting all the coupons, said vertically arranged coupons bearing indicia indicating their non-negotiability when detached from the header.

5. A coupon strip divided vertically into two sections, one of said sections divided horizontally into a series of coupons arranged vertically one above the other and the other section bearing indicia constituting it an additional coupon and forming a header uniting all the coupons, said vertically arranged coupons bearing indicia indicating their non-negotiability when detached from the header and all of said coupons bearing the same identifying number.

6. A coupon strip divided vertically into two sections, one of said sections divided horizontally into a series of coupons arranged vertically one above the other and the other section bearing indicia constituting it an additional coupon and forming an integral header uniting all the coupons and written matter extending respectively across each coupon and the adjacent portion of the header so that such written matter is mutilated by detachment of the coupon from the header.

7. A coupon strip divided vertically into two sections, one of said sections divided horizontally into a series of coupons arranged vertically one above the other and the other section bearing indicia constituting it an additional coupon and forming an integral header uniting all the coupons and written matter extending respectively across each coupon and the adjacent portion of the header so that such written matter is mutilated by detachment of the coupon from the header, said vertically arranged coupons bearing indicia indicating their non-negotiability when detached from the header.

8. A coupon strip divided into two sections, one of said sections divided into a sales record and a series of coupons, the other section constituting an integral header uniting the sales record and the coupons, said header indicated to constitute an additional coupon and all of said coupons bearing indicia indicating their exchange value, the aggregate amount of which is indicated upon the sales record and all of said coupons and said sales record bearing the same identifying number.

9. A coupon strip divided longitudinally into two sections, one of said sections divided laterally into a series of coupons, the other section constituting a header uniting all the coupons and written matter extending respectively across each coupon and the adjacent portion of the header so that such written matter is mutilated by detachment of the coupon from the header.

10. A coupon strip divided longitudinally into two sections, one of said sections divided laterally into a series of coupons, the other section constituting a header uniting all the coupons and written matter extending respectively across each coupon and the adjacent portion of the header so that such written matter is mutilated by detachment of the coupon from the header, and each of said coupons bearing indicia indicating its non-negotiability when detached from the header.

11. A coupon strip divided longitudinally into two sections, one of said sections divided laterally into a series of coupons and the other section constituting an integral header uniting all the coupons, each coupon and the adjacent portion of the header bearing indicia reading across the coupon and the adjacent portion of the header and setting forth the negotiability of the coupon while attached to the header, and the portion of said indicia borne by the coupon alone setting forth the non-negotiability of the coupon.

In witness whereof I have hereunto set my hand this 3d day of January, 1919.

EDWARD I. RICE.
